UNITED STATES PATENT OFFICE.

OTTO THIEME, OF ST. LOUIS, MISSOURI, ASSIGNOR TO MOON-HOPKINS BILLING
MACHINE COMPANY, OF ST. LOUIS, MISSOURI, A CORPORATION OF MISSOURI.

ERROR-KEY FOR CALCULATING-MACHINES.

1,283,597.

Specification of Letters Patent.

Patented Nov. 5, 1918.

Application filed May 18, 1917. Serial No. 169,585.

To all whom it may concern:

Be it known that I, OTTO THIEME, a citizen of the United States, residing at the city of St. Louis, State of Missouri, have invented a certain new and useful Improvement 5 in Error-Keys for Calculating-Machines, of which the following is a full, clear, and exact description, such as will enable others skilled in the art to which it applies to make and use the same, reference 10 being had to the accompanying drawings, forming part of this specification, in which—

Figure 1 is a side elevational view partly 15 in section of my improved error key attachment for calculating machines.

Fig. 1^a is a detail view of the means for restoring the frame containing the key-positioned pins of the setting-up mechanism.

Fig. 2 is a plan view of the keyboard arrangement of said machine.

Fig. 3 is a detail view illustrating the error key connections and its motor control.

Fig. 4 is a side elevational view of the error key and part of the connections controlled thereby.

Fig. 5 is a vertical sectional view illustrating the error key control of the motor.

Fig. 6 is a horizontal sectional view showing the error key control of the motor.

Fig. 7 is a detail view of the error-key operated releasing means for the result keys.

This invention relates to a new and useful improvement in error keys for calculating machines, the object being to provide such a machine with a key of the character described which key will, when positioned, effect a connection between the power shaft which drives the machine and the parts or 35 elements of the machine to be restored when correcting an error. Heretofore adding or calculating machines have been provided with error keys which, when operated, reset the positioned parts in the correction of the error, thus rendering it unnecessary to operate the handle or drive shaft of the machine.

Commercial forms of adding machines, when first put on the market, were uniformly operated by a handle with the result 50 that when an error was made, as in setting up a wrong item on the keyboard, the error key itself had to be operated to restore the key-positioned parts to normal position.

55 This form of error key did not require an

operation of the handle to restore the erroneously positioned parts. Indeed, in the so-called handle-operated eighty-one keyboard machines such as of the Burroughs, Wales and Ellis type, the operation of the 60 handle after an item had been set up on the keyboard, in the absence of any preventing mechanism, would inevitably introduce such item into the register wheels and accumulate it with the items previously introduced 65 therein. In the ten-key type of machine, such as the Standard, and especially those characterized by a transversely movable pin carriage, such as the Dalton, the Sundstrand, and the Moon-Hopkins billing machine, the 70 latter being the type shown in the accompanying drawings, when the keys are successively operated to set up a number, the setting-up devices, including the movable carriage, are displaced, and it is obvious 75 that if the handle, or motor (or either) is operated under these conditions, such a number will be introduced into the totalizer; or if the error key is operated to 80 eliminate a number, the error key must restore all of the positioned parts before the handle or motor is operated. The Standard machine is possibly an exception to this general rule when equipped with the 85 error key attachment of the Wageley and Stocke Patent No. 800,959, dated October 3, 1905, which requires an operation of the handle after the error key is operated, to restore the key-positioned parts. (But in this 90 form, the item is actually introduced by the keys, into the register or totalizer, and the operation of the handle is necessary to subtract, by reversely rotating the totalizer wheels, the last item erroneously introduced 95 thereinto. More recently the trend in both eighty-one and ten key machines has been 100 toward motor drives, which dispenses with the necessity for an operating handle, but even in this type of motor driven machine the error key has usually been relied upon to do the work of restoring the parts to normal position independently of any operation of the motor. In speaking of the operation of the motor, it must not be understood to mean that the motor is still and moves only 105 when the machine is being operated. There are some types of machines so driven, but most commercial forms of machines are driven by constantly running motors which are connected to the main operating shaft of 110

the machine by some form of clutch mechanism to impart to the machine an effective stroke. In all forms of motor driven machines of which I am aware, the operation of 5 the error key to restore the parts does not render the motor operative with respect to the machine, but on the contrary, the error key itself restores the parts independently of any motor drive. As it requires some 10 little power to operate the error key to move the mass of metal under its control, it sometimes happens that the error key is not given a full stroke, in consequence of which the parts are not fully restored to position 15 and improper operations attend subsequent movements of the machine.

In my present invention, the error key is 20 designed to effectively connect the motor to the motor operating shaft of the machine and to position other parts of the mechanism whereby when said operating shaft is making an effective stroke, it will restore all displaced and previously key-positioned parts to normal position. The motor thus 25 does the work and relieves the error key of the necessity of moving heavy parts; and furthermore, there is little or no liability of the parts being left in an abnormal position after operation of the error key, as the 30 error key must not only position certain parts of the machine, but incidentally therewith connect the motor to the operating shaft, which, in making its complete movement, must of necessity restore all the parts 35 as in the normal operation of the machine. In connection with this feature of placing certain parts of the machine under control of the motor driven shaft by the depression of the error key, and coincidentally coupling 40 the motor to the machine, there are locking and interlocking devices which form part of my present invention, all of which will hereinafter be described and afterward pointed out in the claims.

45 In the drawings 1 indicates the base of the machine, 2 the side frames thereof, 3 the typewriter keys, 4 the platen which supports the sheet of paper to be printed upon and which is mounted in the laterally movable 50 paper carriage. 5 are the rack bars of the adding mechanism carrying printing type 6 at their forward ends and 7 and 8 are the totalizer wheels of the adding mechanism. 9 is the laterally movable pin carriage in 55 which the number to be introduced into the register wheels 7 or 8 is set up by operating the digit keys 10 in the keyboard, said carriage being stepped leftwardly at each digit key operation in the manner hereinbefore 60 disclosed in the Hubert Hopkins French Patent No. 383,719 granted January 16, 1908, and his United States application Serial No. 310,739 filed April 9, 1906.

65 11 indicates the motor having worm drive connections to a shaft 12 on which shaft are

mounted driving and driven clutch members, the latter being conjoined to a crank arm 13 connected by a link 14 to rock arm 15 on the main operating shaft 16 of the adding machine mechanism. The means for releasing this driven clutch member and permitting its engagement with the driving clutch member comprises a beveled lug 17 on the driven clutch member 18 which lug co-operates with a bar 19 having a 75 beveled lower edge, as shown in Fig. 6, whereby when said bar 19 is raised, the driven clutch member 18 is forced into engagement with the driving clutch member 18^a by the spring 20. The motor drive thus 80 described and its method of control is substantially the same as that disclosed in Hubert Hopkins United States Patent No. 1,025,698 dated May 7, 1912, and includes, as shown in said patent, a sliding motor bar 85 21 having an inclined face for engagement with the pin 19^a whereby upon the depression of the motor key bar 22 (see Fig. 2), said motor bar 21 will be pulled forwardly to raise the bar 19 and release the driven 90 clutch member 18 which, upon engagement with the driving clutch member 18^a and parts, imparts a complete revolution to the crank arm 13. 23 indicates a motor controlling bar (see Fig. 5) operated by the subtraction key 25 and the multiplier keys 26, whereby when either of said keys is depressed, the motor bar 19 will be lifted and the motor coupled to drive the adding mechanism without necessitating the separate operation of depressing the motor bar 22. 100

My present invention, however, has nothing to do with this multiple control of the motor by the motor key 22, the subtraction key 25, or the multiplier keys 26. 105

In the development of the Moon-Hopkins billing machine disclosed in the Hubert Hopkins French patent and United States application of Hubert Hopkins, before referred to, the constantly running motor 11 110 is utilized to operate the back spacing and carriage return mechanisms of the paper carriage and for this purpose a gear 28 was conjoined to the driving clutch member 18^a for driving a gear 29 on the counter-shaft 115 30. I utilize this counter shaft in the present construction and by providing the same with a fixed clutch member 31 with which co-operates a spring pressed movable clutch member 32 having a pin 33 for co-operating with the inclined lower end of bar 34 which bar is provided with a pin 35 at its upper end for co-operating with an error key connection. The movable clutch member 32 is provided with a cam 36 which 120 cam co-operates with a pin 37 on a bell crank lever 38 connected by a link 39 to the T-shaped lever 40. This T-shaped lever is connected by a rod 41 to restoring means in the form of a plate 42 which is employed 130

to depress any of the raised pins 43 in the laterally movable carriage 9, which pins may have been previously positioned by the operation of the digit keys 10 to represent a number. The rod 39 is provided with a slot in its rear end for engagement with the bell crank lever 40 so that said bell crank lever will be operated at the final limit of the forward movement of said rod. Other means are provided for operating the restoring plate for the pins 43 in the normal operation of the machine, but we are not concerned with this in the present application, as such means are not operative during the movement of the parts incident to the operation of the error key.

It will be observed by referring to Figs. 5 and 6 that there are two clutch driving members 18 and 31, and two clutch driven members 18 and 32, the member 18 being controlled by the motor key 22 and possibly by the subtraction key 25 and any one of the multiplier keys 26 if these mechanisms are included in the machine, while the driven clutch member 32 is controlled only by the error key in the manner now about to be described.

45 indicates the error key in the form of a rod having a button or head at its forward end and connected to the bar 46 which latter has an extension providing an inclined face 46^a which co-operates with the pin 35 on the upper end of bar 34. Thus, when the error key is pressed rearwardly, it will lift the bar 34 and effect a complete rotation of the bar 34 and the cam 36, rocking the bell crank 38 in the manner before described. Bar 46 is provided with a shoulder 46^b which co-operates with a beveled end of the laterally movable bar 47 having a notch in its inner end which notch normally lies in front of the motor bar 21, whereby when said bar 47 is in normal position the motor key 22 and its bar 21 may be operated, but when the bar 47 is displaced by the operation of the error key, the motor bar 22 cannot be operated. The lever 50, before referred to, which co-operates with a lever 50 (see Figs. 2 and 3) which extends across the machine and is provided with means at its opposite end whereby when the error key is operated any of the result keys marked "T," "F. D.," "Ex," "1st P," and "P" will be released if they, or any of them, have been depressed, or are being held depressed, at the time the error key is operated.

65 In Fig. 7, I have shown one means of re-

leasing the result keys upon the operation of the error key, this means consisting in a lug 50^a at the left hand extremity of the lever 50 (see Figs 2 and 7) whereby, when the shoulder 39^a engages and operates said lever 50, as shown in Fig. 3, the lug 50^a will move forward under the hinged locking plate which co-operates with lugs 329 on the bars 328. These bars are supported on levers 330 and 331, the latter of which are 75 connected by a link 332 to a rod 333 which extends forwardly and is connected to one of the result keys so that when said result keys are depressed, the bar 333 will be pulled forward and locate the lug 329 in 80 front of the plate 176, thus holding the result key depressed. In the ordinary operation of the machine, such for instance as disclosed in the Hubert Hopkins Patent No. 1,118,489, dated November 24, 1914, means 85 are operated upon rocking of the main shaft of the machine, to raise the forward edge of plate 176 and release the result keys at about the time the rock shaft is completing its first half stroke of movement. If any 90 of the result keys have been operated and stand depressed at the time the error key in this present application is operated, the movement of the lever 50 will release such 95 result keys and permit them to rise as an incident to the correction of the error following the operation of the error key.

This Patent, No. 1,118,489, also shows a form of multiplying and subtracting mechanism which may be used in connection with 100 the Moon-Hopkins billing machine for which my present invention is especially designed.

The lever 50, before referred to, also has connected to it a link 51 which extends rearwardly so as to co-operate with the bent lower end of the bell crank lever 52 connected to a vertically movable bar 53 identified with the multiplying mechanism, whereby upon the operation of the error key, bar 53 110 will be released so as to render the multiplying plates inoperative.

Bar 40, in addition to operating the restoring plate 42 for the pins 43, also restores the frame 9 to normal position through the 115 medium of a shoulder 40^a on said bar (see Fig. 1^a), which shoulder is designed to engage a pin 60 on a segmental rack 61 pivoted to the frame of the machine. This segment 61 meshes with a pinion 62 meshing 120 with a rack 63 having a projection 63^a on its inner end which is designed to engage and restore the frame 9 whenever the segment 61 is depressed. Any leftward movement 125 of frame 9 is permitted so far as the segment 61 is concerned by reason of the unrestrained upward movement of said segment when bar 40 is locked in its normal position wherein shoulder 40^a is located some distance above pin 60. The pinion 62 also en- 130

gages the rack 64 which is identified with the escapement mechanism operated by the keys. None of these parts, however, form any part of my present invention as they 5 are disclosed in a companion application Serial No. 169,581 filed by me of even date herewith. The only feature in which the present application is concerned is the depression of bar 40 whenever the error key 10 is operated, which bar 40 returns the frame 9 and its controlling escapement mechanism to their starting positions respectively and operates the restoring plate 42 to restore the pins 43 in the frame 9 so that another ex- 15 ample may be set up on the keyboard.

From the above, it will be observed that with respect to the motor drive for the machine there are two clutch controlling keys which will cause said motor to effectively 20 drive parts of the adding mechanism. The first key which may be designated as the regular motor key will operate the main rocking shaft of the machine to introduce a number set up on the keyboard into the 25 totalizer wheels and record said number and, in addition to this, will restore certain parts to their normal or starting position for another operation. Whereas, the second motor controlling key operative to correct an 30 error will take power from the motor at a different point and only operate the restoring parts of the adding mechanism, thus causing the motor to perform the actual work of restoration and relieving the error 35 key from the necessity of moving said restoring parts.

What I claim is:

1. In a calculating machine, the combination with two power driven shafts, an adding 40 mechanism, a motor key for effectively connecting one of said shafts to said adding mechanism to register a number in the totalizer thereof and restoring said adding machine parts in readiness for another operation, and an error key for effectively connecting the other of said shafts to the restoring parts only of said adding mechanism.

2. In a calculating machine, the combination of register wheels; actuating racks 50 therefor, key-positioned devices for controlling the excursions of said racks, a power shaft, and an error key for placing said power shaft in control of said key-positioned devices for returning them to normal 55 position independently of any operation of said register wheels.

3. In a calculating machine, the combination of a totalizer, its actuating devices, 60 key-operated setting-up mechanism, motor-driven parts, means for effectively connect-

ing said motor-driven parts to register a number in said totalizer and restore said actuating devices and said setting-up mechanism to their starting position in readiness for another operation, an error key, and 65 means operated by said error key for enabling and disabling the operation of certain parts of the setting-up mechanism, said error key also effectively connecting said motor drive to such parts only as are to 70 be restored to starting position when an error is made.

4. In a calculating machine, the combination with an adding mechanism, setting-up devices therefor, a keyboard containing digit 75 keys for operating said setting-up devices, said keyboard also containing result keys, a main operating shaft for the adding machine which is operated when a number is being introduced into said adding mech- 80 anism and also when said adding mechanism is yielding a total, a motor driven shaft, a motor key for effectively connecting said shaft to the main operating shaft of said adding mechanism in the operations of ac- 85 cumulating and yielding numbers, an error key, and means operated by said error key for locking the digit keys in said keyboard against operation, releasing any result keys which may have been operated, disabling 90 parts of said adding mechanism, and effectively connecting said motor drive to said setting-up devices, to restore them to normal or starting position in readiness for another digit key operation. 95

5. In a calculating machine, the combination with an adding mechanism, setting-up devices therefor, a keyboard containing digit 100 keys for operating said setting-up devices, said keyboard also containing result keys, 105 a main operating shaft for the adding machine which is operated when a number is being introduced into said adding mechanism and also when said adding mechanism is yielding a total, a motor driven shaft, 110 a motor key for effectively connecting said shaft to the main operating shaft of said adding mechanism in the operations of accumulating and yielding numbers, an error key, and means operated by said error key for locking the digit keys in said keyboard against operation, and effectively connecting said motor drive to said setting-up devices, to restore them to normal or starting position in readi- 115 ness for another digit key operation.

In testimony whereof I hereunto affix my signature this 10th day of May, 1917.

OTTO THIEME.
